TOOL FOR APPLYING CONNECTORS TO
ENERGIZED TRANSMISSION LINES
AND THE LIKEDavid C. Hubbard, Centralia, Mo., assignor to
A. B. Chance Company, Centralia, Mo., a cor-
poration of Missouri

Application January 5, 1946, Serial No. 639,438

5 Claims. (Cl. 81—53)

1

The present invention relates to tools for applying electrical connectors to energized transmission lines and the like, and is particularly concerned with an improved tool that is adapted to apply connectors of the split-bolt type with a jumper wire or other conductor that is to be secured to the transmission line conductor.

One of the objects of the invention is the provision of an improved tool for applying split-bolt connectors to an energized conductor which is adapted to hold the jumper wire or a wire loop in proper position against the gripper contact of the connector nut during the installation of the connector without the aid or need for any auxiliary tools, with the jumper or loop arranged below the conductor.

Another object of the invention is the provision of an improved tool for removing split-bolt connectors from energized power lines and for removing and holding jumper wires or loops during this operation in such manner that jumper wires, which may be energized from another source, will not be a hazard, but will be properly controlled.

The tool is, of course, confined to installations or connectors which have been previously installed by a similar or the same tool, with the jumper wire below the conductor, and not above it nor twisted about it.

Another object of the invention is the provision of an improved tool of the class described, which is provided with a self-aligning, self-centering mechanism in the head, for gripping the split bolt of a connector, which mechanism is actuated by spiral grooves in the cap so that a split-bolt may be very quickly installed and gripped.

Another object of the invention is the provision of an improved tool of the class described, which may be provided with interchangeable sockets for the nut so that it is adapted to fit a plurality of split-bolt connectors of different sizes.

Another object of the invention is the provision of an improved socket lock mechanism for a tool of the class described, which does not require the use of any tools, and which effects an absolutely certain securement of the socket so that there is no danger of the socket getting loose during the operation of the tool.

Another object of the invention is the provision of an improved tool of the class described which is provided with means on either side of the socket positioned and designed to hold a jumper or loop wire in position against the gripper portion of the split-bolt nut.

2

Another object of the invention is the provision of an improved tool which has its sliding mechanism so constructed as to maintain alignment of the parts, and which is so insulated by Bakelite tubing and the use of insulating operating rods that the amount of exposed metal is reduced to a minimum and the possibility of flash-over to ground or between phases is practically eliminated.

10 Another object of the invention is the production of an improved tool of the class described for applying split-bolt connectors which involves the use of a single pole so that a single operator may apply these connectors with a minimum amount of labor and time and so that the number of tools required is reduced to a minimum.

Other objects and advantages of the invention will be apparent from the following description 20 and the accompanying drawings, in which similar characters of reference indicate similar parts throughout the several views.

Referring to the drawings, of which there are two sheets,

25 Fig. 1 is a front elevational view of a split-bolt connector tool embodying the invention;

Fig. 2 is a side elevational view in partial section;

Fig. 3 is a fragmentary vertical sectional view 30 taken on the plane of the line 6—6 of Fig. 1 and showing the parts as they appear after the connector nut has been driven home and the connector and jumper wire have been secured on the energized conductor, but the tool has not yet been removed;

Fig. 4 is a top plan view of the tool of Figs. 1 to 3, with wires in the tool, taken on the plane of the line 4—4 of Fig. 1, except that wires have been added;

Fig. 5 is a sectional view taken on the plane of the line 5—5 of Fig. 1, except that a wire has been added;

Fig. 6 is a fragmentary sectional view taken on the plane of the line 6—6 of Fig. 1, except that wires have been added, showing the tool in the position which the parts assume when it is ready to be placed on the energized conductor;

Fig. 7 is side elevational view of one of the detachable sockets for nuts of different sizes;

Fig. 8 is a sectional view taken on the plane of the line 8—8 of Fig. 7 through the socket;

Fig. 9 is a sectional view taken through one form of split-bolt connector nut, which is provided with one form of gripper for engaging the jumper wire; and

Fig. 10 is a fragmentary side elevational view

showing the preferred shape of the springs which grip the jumper wire.

The present tool is adapted to apply to energized conductors, jumper wires or loops of any of the usual sizes and split-bolt connectors of various standard constructions, provided the split-bolt has a noncircular head with two opposite flattened portions to be engaged by the head of this tool, and provided the connector has a nut of shape or size to fit the socket wrench.

It is also adapted to apply the split-bolt connectors disclosed in my prior application, Ser. No. 624,497, filed October 25, 1945, issued May 31, 1949, as Patent No. 2,471,957, entitled Electrical connectors.

Such split-bolt connectors are illustrated generally in Figs. 6 and 9, and they include a split-bolt 10 and a nut 11, provided with a wire gripper 12. The nut may consist of a standard hexagonal nut provided with a threaded bore 13.

The gripper may consist of any metal member which has an upper groove 14 for receiving the jumper wire 15, and one or more downwardly extending legs 15a, with means 16 on said legs for engaging below the nut to keep the gripper on the nut, but to permit the nut to rotate relative to the gripper.

The split-bolt has a noncircular head 17 and a threaded shank 18, which has a pair of legs 19 and 20 separated by a slot or groove 21 that extends up into the head and is adapted to receive the energized conductor wire 22.

The legs 15a of the gripper 12 are located in the slot 21 so that they slide in the slot as the nut 11 rotates and is threaded on the shank 18.

While the head 17 of the split-bolt may be hexagonal or square or any standard shape, it need only have two opposed flat surfaces 23, 24, such as that shown in my prior application, to be engaged by the head of this tool.

The tool is provided with an elongated operating pole 25, preferably cylindrical in shape and made of properly dried wood, impregnated and covered at its outer surface with an insulating varnish such as a Bakelite varnish; and the length of this pole depends upon the voltage with which the tool is to be operated.

At the upper end of the pole 25 the pole is provided with the mechanism of the present tool, but adjacent its lower end it is provided with a sliding tubular handle 26 for controlling an actuating rod 27, by means of which the mechanism is actuated.

The handle 26 may consist of a cast metal cylindrical sleeve, having at its upper end on one side an auxiliary integral lug 28 provided with a cylindrical socket 29 for the end of the wooden rod 27.

The wooden rod is of similar insulating characteristics to the pole 25, and only slightly shorter in length, so that the handle 26 is located near the lower end of the pole, the upper portion of the pole insulating the tool from the hands, and the rod 27 insulating the handle from the tool mechanism.

The rod 27 may be secured in the socket 29 by a metal pin 30 passing through the rod and socket, and riveted over on the outside of the socket.

At its upper end the pole 25 is preferably provided with a sleeve of Bakelite tubing 31, which extends downward for a distance of approximately a foot to cover metal parts and improve the insulation and reduce the possibility of flash-over from adjacent energized conductors.

The rod 27 is also preferably covered with a short section of insulating Bakelite tubing 32, extending from a lower cross head 33 to the head 34. In each case the Bakelite tubing is preferably impregnated and covered with an insulating varnish.

The cross head 33 forms the lower end of a slider structure which includes the rod 27, a pair of insulating guide rods 35, 36, and the head 34. 10 The head 34 includes a cast metal body 37, which has an integral depending tubular member 38 provided with a cylindrical socket 39 for receiving the tube 32 and rod 27. The tube and rod are pinned in the socket 39 by a transverse metal pin 40 passing through the rod, tube, and walls of the socket 39 and riveted over on the outside.

This fixes the tube 32 to the rod, and it is only necessary to secure the cross head 33 to the tube 32 and rod 27 by a transverse pin 41, which passes through the cross head and engages a groove 42 in the tube 32, thus rendering it unnecessary to bore through the rod or tube, which might reduce their strength at this point.

25 The cross head 33 has a pair of laterally extending arms 43, 44 joined by a body, which has a concave curve 45' for clearing the outside of the tube 32 on the operating pole 25. Each of the arms 43, 44 is provided with a cylindrical portion, having a socket for receiving the guide rods 35, 36, which are fixedly pinned in these sockets by the through pins 45 in a manner similar to that previously described.

30 The operating head 34 also has a pair of sockets located in the partially cylindrical portions 46, 47 for receiving the upper ends of the rods 35, 36, which are pinned in these sockets so that the head 34 is fixedly secured and supported on the rod 27 and is secured to the cross head 33 by the two additional guide rods 35, 36, providing a relatively rigid support for the head 34.

35 The head 34 has a generally cylindrical body, except for the outwardly projecting socket portions 46, 47, which extend radially from the head; and it is preferably provided with a pair of depending guide prongs 48, 49, which are spaced from the socket lugs 46, 47 sufficiently to form a pair of aligned slots 50, the upper portion of which is partially cylindrical at 51.

40 The prongs 48 and 49 are adapted to be used 50 to hook the tool on the energized conductor of a transmission line, such as the conductor 22. The slot 50 is adapted to be aligned with the slot 21 of the split bolt 10 when the bolt is carried by the head 34 so that the prongs 51 actually guide the energized conductor 22 into the slot 21 of the split bolt.

45 For this purpose the slot 50 must be centrally located in the head and must extend diametrically across the center of the head. The body 52 of the head 34 is formed with a centrally located hub 53 projecting upward from the circular body and having a cylindrical bearing surface 54.

50 The hub 53 has a threaded bore 55 for receiving a screw bolt 56, which may be provided with a thrust washer 57 or an enlarged head for retaining a rotating cam 58. The cam 58 consists of a circular disc of metal provided with a pair of upwardly projecting radial wings 59 for engagement with the fingers to rotate the cam, and with a central bore 60 for receiving the hub 53, on which it is mounted for rotation.

55 The body 52 of the head has an upper plane surface 61, and the cam 58 has a lower plane surface 62, the latter being provided with a spirally

extending groove 63 located in the lower surface 62 for receiving the pins 64, 65.

The groove 63 is preferably rectangular in cross section, and the pins 64, 65 may be substantially cylindrical, with plane ends. The length of the hub 53 is less than the thickness of the cam plate 58 so that the cam plate rotates freely on the hub; and in so doing the pins 64 or 65 riding in the groove 63 are moved radially inward or outward, depending on the direction of rotation of the cam.

The head body 52 is also provided with a pair of radially extending cylindrical bores or sockets 66, 67 communicating with upwardly extending apertures 68, 69, the latter taking the form of elongated radial slots for passing and guiding the pins 64, 65.

The bores 66, 67 slidably support the cylindrical jaws 70, 71. The inner plane surfaces 72, 73 are adapted to grip the opposite flat sides 23, 24 of the head 17 of a split bolt. The pins 64, 65 prevent rotation of the jaws 70, 71 in their sockets 66, 67 by virtue of the pins being located in the slots 68, 69, and the pins may be secured by a tight frictional fit in the bores 74 in each jaw 70, 71.

The slope of the spiral cam groove 67 on the bottom of the cam plate 58 is very gradual so that, as this cam is rotated, the jaws 70, 71 are moved slowly, and the cam is adapted to effect a wedging action with the pins 64, 65 so that when the jaws 70, 71 engage a split-bolt head the cam holds them, thereby wedging against the pins 64, 65 in the groove 63.

Thus the split-bolt of a connector may be held in the head 34 in suitable position to engage an energized conductor 22, which is guided into place by the prongs 48, 49.

The pole 25 is provided at its upper end with a suitable wrench socket, such as the socket 75; and arrangements are preferably made so that this socket is interchangeable with others of different sizes for use on split-bolt connector nuts of different sizes. Therefore, the upper end of the pole is provided with a noncircular socket 76, communicating with another cylindrical socket 77 for receiving the noncircular portion 78 of a shank and the cylindrical reduced end portion 79.

The latter end portion 79 may be pinned in its socket by a transverse metal pin 80, which is confined in its bores 81, 82 by being placed inside and under the Bakelite tube 31.

A cylindrical reinforcing ring of metal 83a may surround the wood of the pole 25 at its uppermost end, clamping the pole against the reduced cylindrical portion 83, which, however, has grooves for receiving the corners or radial flanges 78 of a non-circular portion 78.

The shank 78 has an upper cylindrical portion 83, which carries a substantially cylindrical body 84 that is adapted to rotate in a guide member 85. The body 84 has an annular groove 86 about its outer cylindrical surface, the groove being rectangular in cross section, and adapted to receive the end of a screw bolt 87, which is threaded through the wall of the guide member 85 and located in the slot 86 to permit rotation of the body 84 inside the guide 85, but to prevent any relative axial movement between these two members.

The cylindrical body 84 is thus adapted to be rotated by the pole 25 to actuate the wrench 75 and to apply or remove a nut 11. In order to provide for a plurality of different sockets, this body has an upper reduced cylindrical portion 88, which is provided with a spring pressed plunger 89.

The spring pressed plunger 89 is provided with an enlarged cylindrical head 90 and a cylindrical stem 91. The head 90 is located in a bore 92 and

engages a helical coil spring 93, the other end of which engages the end of the bore 92. The stem 91 passes through a smaller counterbore 94 and projects from this counterbore into a slot 95 of a socket 75. The head 89 projects into a cylindrical portion 96 of a bore which communicates with the lower end of the socket through a slot 97.

The shoulders provided by the portions 98 of the bore 96, which are toward the lower side of the bore on either side of the slot 97, are the retaining shoulders on the socket, which engage the head 90 on plunger 89. The plunger 89 is, however, urged into the engaging position shown in Fig. 6, and can be disengaged by being pushed inward until its stem 91 goes into a bore 99 in the body 85 and the head 90 clears the shoulders 98.

At this time the socket can be removed because at the opposite side of the socket there is merely a slot 95. One of the sockets is shown in Figs. 7 and 8, and it comprises a substantially cylindrical metal body, having a lower cylindrical tubular portion 100, which fits about the reduced portion 88 of the rotating body 84 and inside a cylindrical bore 101 in the guide 85.

Above the cylindrical tubular portion 100 there is a radially projecting flange 102, the annular surface 103 of which serves to engage the top of the guide member 85 and to align the plunger head 90 with its socket 96 in an axial direction. The upper outer part of the socket 75 may comprise a tubular cylindrical portion 104 that is provided with a hexagonal socket 105 for engaging a hexagonal nut.

The shoulders 106 in the socket 105 determine the extent to which the nut goes into the socket 105, and to save material there may be a counterbore 107 and through bore 108 in the socket member 75.

The member 85 comprises a guide for rotatably supporting the body 84 carried by the end of the pole 25 for rotating the socket 75. Therefore, the body 85 comprises a generally cylindrical metal member having an outer cylindrical surface and having the inner bore 101. The cylindrical body 85 has projecting from it a radially extending bore 109 provided with a radially extending bore 110 adapted to register with the plunger 89.

The bore 110 has a plunger 111 mounted for sliding movement in this bore for actuating the plunger 89. The plunger 111 may consist of a pair of cylindrical head members 112, 113 joined by a reduced cylindrical shank 114.

The plunger 111 may be retained in its bore 110 by a transverse pin 115, which is eccentrically located with respect to the reduced cylindrical portion 114 so as to miss it, but so that pin 115, which is riveted in the lug 109, engages the annular surfaces 116 on the inner end of each of the members 112, 113. Thus the plunger 111 may reciprocate freely except as it is influenced by the spring pressed plunger 89, and plunger 111 is of sufficient length so that it projects from its bore 110 when it is engaging the plunger 89 in the position of Fig. 6.

It is also of sufficient length so that, when pressed inward, plunger 111 moves plunger 89 far enough to cause head 90 to clear its socket 96. Thus the button 112 is the actuating member for releasing the socket latching plunger 89; but, as the body 84 rotates in the guide 85 the socket supporting body 84 must be turned to the proper radial position for registry between plungers 111 and 89 before the socket can be removed.

In Fig. 6 the socket supporting member 84 is

shown in the proper rotative position for engagement between the plunger 111 and plunger 89 so that a mere push on the button 112 will unlatch the socket 75.

Other sockets of different sizes or having differently shaped nut-engaging surfaces 105 may be substituted, thus making the tool one of universal application to various types of split-bolt connectors.

In addition to the radially projecting lug 109, the body 85 has the radially projecting, partially cylindrical portions 117, 118, 119. The portions 117, 119 are provided with bores 120, 121 for slidably receiving the wooden rods 36, 38 so that the member 85 is guided on the rods 36, 38 as it is moved upward and downward by means of the handle 26 and pole 25. The projecting portion 118 of the guide body 85 also has a cylindrical bore 122 for slidably receiving the Bakelite tube covered rod 27, 32, which also guides the head 85 in its up-and-down sliding motion.

The projecting portions 117, 119 of the guide body 85 preferably have a pair of radially extending supporting lugs 123, 124 (Fig. 5) for the purpose of carrying a pair of spring clips 125 to 128 on each lug 123, 124. The forward surfaces 129 of each lug 123, 124 are plane and are so located that the line of division 130 between the spring clips is diametrically located, and each clip of each pair is located on the opposite sides of this diametrical line or plane.

The lugs 123, 124 are provided with a pair of threaded bores for receiving the two screw bolts 131, which pass through each pair of clips at their securing flanges 122 to fasten them to the lugs.

The spring clips 125 to 128 may all be similar in construction and shape, and each clip has a relatively flat attaching flange portion provided with bores for receiving the screw bolts 131.

The spring clips 125 to 128 are preferably shaped as shown in Figs. 6 and 10 so that they exert a downward force on the jumper wire to hold it in the groove 14 of the split bolt connector wire gripper 12.

Thus, in Fig. 6 both of the spring clips are shown already engaging the wire 15 so that the jumper wire is firmly held; and even though struck against some object or jarred, the jumper cannot easily become disengaged.

Referring to Fig. 2, each clip is bent outward at 133 and backward with an easy bend at 134 to form a partially cylindrical groove between two clips. Thereafter the clips extend diagonally upward with substantially straight portions 135, and they contact each other at the outward bends 136, and have outwardly extending horns 137, which form a receptive camming surface for receiving an energized conductor so that the conductor cams the clips apart until this conductor is also received in between the two clips.

The operation of my connector applying tool is as follows: The split-bolt is disconnected from its nut. In applying the connector to a tool, the split-bolt 10 is placed in the centrally located socket 138 of the head 34 between the gripping jaws 10, 71, these jaws having been withdrawn sufficiently by rotating the cam 58.

The cam member may then be rotated in the opposite direction until the jaws grip the opposed noncircular surfaces 23, 24 on the head of the split-bolt, and the cam effects a slight wedging action, holding the head of the split-bolt in the operating head 34. The slot 21 of the split-bolt should, of course, be located so that it extends parallel to the jumper wire 15, which is to

be placed between the spring clips 125-128 in the position shown in Fig. 6.

The nut 11 is placed in the socket 75, with its gripper 12 extending uppermost and the groove 14 of the gripper extending parallel to the slot 21. Then the wire 15 may be placed between the spring clips 125-128 in the groove of the gripper 12 of the nut. At this time the device is in the condition disclosed in Fig. 6, except that it is not hanging on the energized conductor 22.

The operator may then lift the split-bolt connector with its bolt, nut, and the jumper wire by means of the pole 25 until the prongs 49 rise above the energized conductor 22, so that these prongs may be hooked over the conductor, aiding in guiding the conductor into the slot of the split-bolt connector, where the device will hang of its own weight.

This should be done preferably by holding the pole 25 at the handle 26 so that the weight of the pole 25 and its associated parts will keep the socket 75 and jumper wire 15 in the lowermost position in Fig. 6, with the device open below the prongs 48, 49 for insertion of the energized conductor 22.

After the device is hooked on the energized conductor 22, the operator may then grasp the handle 26 with one hand and the pole 25 with the other hand, and the pole 25 may be pushed upward, while pulling down on the handle 26. This will cause the body 85 to rise with its spring clips 125-128, carrying with it the socket 75, nut 11, and jumper wire 15.

As the spring clips 125-128 engage the energized conductor 22, they will be cammed apart by the end portions 131 until the conductor 22 contacts the conductor 15.

Before this time, however, the nut 11 may come into engagement with the shank 18 of the split-bolt 10; and the reduced cylindrical end of the split-bolt, shown at the bottom of this bolt in Fig. 6, aids in the alignment of the nut and bolt.

While the nut is engaging the bottom of the threads on the split-bolt, the operator may turn the pole 25, during which action the supporting body 84 for the socket 75 rotates in the guide member 85, rotating the nut 11 and causing it to be threaded on the bolt 10.

During this action the gripper 12, carried by the nut 11, slides upward in the slot 21, carrying with it the jumper wire 15 until the jumper wire 15 is brought into tight engagement with the energized conductor 22, which is forced into the base of the slot 21.

The nut 11 may thus be brought into tight clamping relation with the two wires 15, 22 confined in the slot 21 between the base of the slot 21 and the gripper slot 14.

The tool may then be withdrawn by pulling downward on the pole 25, which will withdraw the socket 75 from the nut 11. The tool may be removed from the split-bolt by pushing upward on the handle 26, the bolt head 17 of the bolt sliding from between the two jaws 10, 71.

The jaws are preferably so arranged that they grip the bolt head tight enough to retain its weight, but not so tightly that the tool cannot be pushed off the head as just described.

When a split-bolt connector is to be removed, the jaws are first previously adjusted to the proper gripping position by trying another split-bolt in the head 34 and adjusting it so that the jaws hold the bolt, but can be slid on or off the bolt. Then, with the device in the position of Fig. 2, the prongs 48, 49 may be hooked over the

energized conductor in such manner that the jaws 10, 71 can be pulled down on the opposite sides of the head of the split bolt.

Thereafter the handle 26 is held down, while the pole 25 is pushed up, until the spring clips 125-128 engage the two conductors and the socket 75 engages the nut 11. In this engagement of the nut the pole may have to be rotated slightly to bring the socket into alignment with the sides of the nut.

Thereafter the pole 25 may be rotated in such direction as to unscrew the nut from the split-bolt 10; and as this action takes place, the body 85 will move downward from the energized conductor 22 until the spring clips release the energized conductor 22 and the nut 11 moves off the end of the bolt 10. Then the spring clips will still hold the nut 11, eliminating any possibility of dropping of either of these members, which might result in a short circuit.

If, perchance, difficulty is encountered in adjusting the jaws 76 and 71 until they are sufficiently tight to lift the split-bolt off the energized conductor 22, such action would be immaterial, as the energized conductor 22, supported by poles, would keep the split-bolt from rotating; and after the nut has been removed and the tool has been lifted from the wire, the split-bolt can be retrieved by merely tipping it until it falls off the wire.

It will thus be observed that I have invented an improved tool for applying split-bolt connectors, which will not only apply the connectors, but can also be used in removing them. My tool holds the nut and jumper wire securely during the application or removal so that the danger of dropping the jumper wire is reduced to a minimum.

The present tool may be used with interchangeable sockets on split-bolt connectors of different sizes and upon various different types of split-bolt connectors which have a bolt with opposed wrench-engaging surfaces and a nut.

The mechanism for holding the split-bolt is self-aligning and self-centering, and the mechanism does not require a screw driver, wrench, or other tools. The application of split-bolts is accomplished by means of a single pole operation, which may conveniently be handled by a single operator.

The present tool is sturdy and adequately insulated against moisture, and the amount of exposed metal is so reduced that the possibility of flash-over to ground or between phases, due to the use of the tool, is substantially eliminated.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a tool for manipulating split-bolt connectors, the combination of an elongated wooden pole with a metal fitting carried by its upper end and having a pair of laterally projecting arms, a pair of upwardly extending spring clips located on each side of said arms, said spring clips being formed with spreading ends, engaging humps, and a recess below the humps for retaining a tap wire, a wrench socket member carried by said fitting and being provided with a socket

for receiving the nut of a split bolt connector, said socket having a through aperture for passing the split bolt, a sliding head movably mounted on said pole, said sliding head being mounted upon a plurality of insulating rods, guides carried by said fitting for said rods, whereby the head may be slid into proximity with the wrench socket and away from the wrench socket, said fitting being provided with guides for said insulating rods, a cross-head for joining lower portions of said insulating rods below said guides, one of said rods being extended downwardly, and being provided with a handle sliding on said pole, said wrench socket being rotatably mounted in said fitting, and said head being provided with means for gripping the head of a split bolt, whereby the tool may be hung on an energized conductor and brought into connection with a tap wire carried by said clips, by pulling downwardly on said handle or pushing upwardly on said pole, the pole rotating to cause the nut to be threaded on the split bolt, with the tap wire below the transmission wire.

2. In a tool for manipulating split-bolt connectors, the combination of an elongated wooden pole with a metal fitting carried by its upper end and having a pair of laterally projecting arms, a pair of upwardly extending spring clips located on each side of said arms, said spring clips being formed with spreading ends, engaging humps, and a recess below the humps for retaining a tap wire, a wrench socket member carried by said fitting and being provided with a socket for receiving the nut of a split-bolt connector, said socket having a through aperture for passing the split bolt, a sliding head movably mounted on said pole, said sliding head being mounted upon a plurality of insulating rods, guides carried by said fitting for said rods, whereby the head may be slid into proximity with the wrench socket and away from the wrench socket, said fitting being provided with guides for said insulating rods, a cross-head for joining lower portions of said insulating rods below said guides, one of said rods being extended downwardly, and being provided with a handle sliding on said pole, said wrench socket being rotatably mounted in said fitting, and said head being provided with means for gripping the head of a split bolt, whereby the tool may be hung on an energized conductor and brought into connection with a tap wire carried by said clips, by pulling downwardly on said handle or pushing upwardly on said pole, the pole rotating to cause the nut to be threaded on the split bolt, with the tap wire below the transmission wire, said sliding head being formed with a downwardly extending guiding prong on each forward side, and being provided with a pair of jaws slidably mounted on said head, each jaw having a pin, and a rotatable member having a spiral slot for receiving said pin, whereby said rotatable member is adapted to actuate the jaws into clamping relation with the head of the split bolt connector.

3. In a tool for applying split bolt connectors and a conductor to an energized line, the combination of an insulating pole supporting said tool, the said pole being provided at its upper end with a metal member having a shank secured in said pole, and a metal sleeve enclosing the end of the pole and providing an annular seat, said shank supporting a socket engaging member, and said socket engaging member having a cylindrical bearing surface and a reduced cylindrical

portion for reception in a complementary bore in a socket wrench member, a rotatable guide member having a cylindrical bore for receiving said cylindrical bearing surface and resting upon said annular seating surface, said guide member having outwardly extending lugs provided with a plurality of bores, a bolt supporting head carried by a plurality of sliding rods, the said rods being slidably mounted in said bores for movement longitudinally of the pole, said bolt supporting head having gripping jaws for gripping the head of a split bolt and holding it in centered position with its shank depending toward the pole, the said rods being joined at their lower end by a cross-head, and the said cross-head having a partially cylindrical formation for engaging the outside of said tube surrounding said pole, the bolt rotating in said guide member to rotate a socket wrench carried by the reduced cylindrical portion, and the pole sliding upward relative to said guide rods to bring the nut carried by the socket wrench into engagement with the bolt.

4. In a tool for applying split bolt connectors and a conductor to an energized line, the combination of an insulating pole supporting said tool, the said pole being provided at its upper end with a metal member having a shank secured in said pole, and a metal sleeve enclosing the end of the pole and providing an annular seat, said shank supporting a socket engaging member, and said socket engaging member having a cylindrical bearing surface and a reduced cylindrical portion for reception in a complementary bore in a socket wrench member, a rotatable guide member having a cylindrical bore for receiving said cylindrical bearing surface and resting upon said annular seating surface, said guide member having outwardly extending lugs provided with a plurality of bores, a bolt supporting head carried by a plurality of sliding rods, the said rods being slidably mounted in said bores for movement longitudinally of the pole, said bolt supporting head having gripping jaws for gripping the head of a split bolt and holding it in centered position with its shank depending toward the pole, the said rods being joined at their lower end by a cross-head, and the said cross-head having a partially cylindrical formation for engaging the outside of said tube surrounding said pole, the bolt rotating in said guide member to rotate a socket wrench carried by the reduced cylindrical portion, and the pole sliding upward relative to said guide rods to bring the nut carried by the socket wrench into engagement with the bolt, and a socket wrench having at one end a noncircular socket for engaging and receiving a nut, and having at its other end a cylindrical socket for receiving said reduced cylindrical portion, said reduced cylindrical portion also having an outwardly spring pressed plunger for engaging in an aperture in the side wall of the cylindrical socket portion of the socket wrench for holding the socket wrench on said reduced cylindrical portion.

5. In a tool for applying split bolt connectors and a conductor to an energized line, the combination of an insulating pole supporting said tool,

the said pole being provided at its upper end with a metal member having a shank secured in said pole, and a metal sleeve enclosing the end of the pole and providing an annular seat, said shank supporting a socket engaging member, having a cylindrical bearing surface and a reduced cylindrical portion for reception in a complementary bore in a socket wrench member, a rotatable guide member having a cylindrical bore for receiving said cylindrical bearing surface and resting upon said annular seating surface, said guide member having outwardly extending lugs provided with a plurality of bores, a bolt supporting head carried by a plurality of sliding rods, the said rods being slidably mounted in said bores for movement longitudinally of the pole, said bolt supporting head having gripping jaws for gripping the head of a split bolt and holding it in centered position with its shank depending toward the pole, the said rods being joined at their lower end by a cross-head and the said cross-head having a partially cylindrical formation for engaging the outside of said tube surrounding said pole, the bolt rotating in said guide member to rotate a socket wrench carried by the reduced cylindrical portion, and the pole sliding upward relative to said guide rods to bring the nut carried by the socket wrench into engagement with the bolt, and a socket wrench having at one end a noncircular socket for engaging and receiving a nut, and having at its other end a cylindrical socket for receiving said reduced cylindrical portion, said reduced cylindrical portion also having an outwardly spring pressed plunger for engaging in an aperture in the side wall of the cylindrical socket portion of the socket wrench for holding the socket wrench on said reduced cylindrical portion, the said spring pressed plunger being located inside of said guide member in an otherwise inaccessible position, and said guide member having a sliding push rod projecting from the guide member and located to engage the end of said spring pressed plunger when the push rod and plunger are rotated into registry so that the push rod may be used to retract the plunger to release the socket wrench member.
